UNITED STATES PATENT OFFICE.

BENJAMIN B. ENGLANDER, OF BROOKLYN, NEW YORK, ASSIGNOR TO ENGLANDER SPRING BED COMPANY, OF BROOKLYN, NEW YORK.

SPRING-MATTRESS.

1,297,552.

Specification of Letters Patent. Patented Mar. 18, 1919.

Application filed September 23, 1915. Serial No. 52,143.

To all whom it may concern:

Be it known that I, BENJAMIN B. ENGLANDER, a citizen of the United States, residing at Brooklyn, in the county of Kings 5 and State of New York, have invented certain new and useful Improvements in Spring-Mattresses, of which the following is a specification.

This invention relates to improvements in 10 springs or spring mattresses, it more particularly relating to an improved side guard by means of which the soft or stuffed mattress is prevented from slipping, spreading and sagging over the edges of the 15 spring, the object of the invention being to provide an improved side guard for each lengthwise extending edge of the spring simple in construction, durable in use and efficient to prevent the flattening and consequent spreading, as well as the slipping of 20 the stuffed mattress over the edges of the spring.

A practical side guard requires that it shall have a certain amount of flexibility or 25 resiliency in order that it will return to its normal position and also that it be stretched under tension. One of the most practical and efficient side guards is that form thereof which is made of a metallic fabric, but a 30 cable guard will to a certain extent answer for the cheaper forms of springs provided it is properly made and supported and has the proper amount of resiliency imparted thereto, and has means for giving it 35 sufficient lengthwise tension and also provided it is connected with the bed spring in such manner that the stuffed mattress cannot bulge between the connecting points to any appreciable extent, and it can, more 40 over, be made somewhat less expensive than the metallic fabric side guard and therefore can be more readily used with the cheaper forms of springs than can the metallic fabric side guards.

45 The object, therefore, of the present improvement is to provide an improved side guard which can be made up of a cable suitably connected with the spring bottom and with the bottom-supporting transverse irons 50 so that while it will yield to a certain extent when the user sits upon the edges of the stuffed mattress, it will nevertheless return to its normal position when such weight is removed.

In the drawings accompanying and forming a part of this specification, Figure 1 is 55 a perspective view of one form of the present improvement; Fig. 2 is a side view, enlarged, of the improvement shown in Fig. 1, the left-hand portion thereof illustrating 60 the structure shown in Fig. 1 while the right-hand portion thereof illustrates a modification of the structure shown in Fig. 1; Fig. 3 is a cross-sectional view taken in line 3—3, Fig. 2; Fig. 4 illustrates a perspective view of a slightly different form 65 from the structure shown in Fig. 1; and Fig. 5 is an enlarged side view of the structure shown in Fig. 4.

Similar characters of reference indicate 70 corresponding parts in the several figures of the drawings.

A conventional form of spring mattress is shown in all of the figures of the drawings, this comprising a spring or spring bottom 75 2, usually of metallic form, either of woven wire or otherwise as occasion may require, connected at its ends and stretched under tension between a pair of end binding members 3 which in turn are connected by a 80 series of helical springs 4 with transverse irons 5. These transverse irons are provided at their corners, one at each, with an upstanding lug or post 6' for the attachment of the side guard. In all the figures of 85 the drawings the side guard is composed of a cable, which may be of any suitable form, but in the preferred form shown it is composed of a series of spirally twisted or interwoven wires forming what is known as 90 a rope-formed edge or cable. In the form shown in Figs. 1 and 2 this cable is connected directly at its ends with the upstanding lugs hereinbefore referred to. These lugs are formed with hooks for the 95 reception of similar hooks or eyes secured to the ends of the cable. Connecting this cable with the bottom is a series of helical or spiral springs, some as 6, perpendicularly located and others as 7, diagonally located, 100 which tend not only to support the cable but also to give to it a certain amount of tension thereby to return it to its normal position when moved away from such position. In practice the diagonal springs at one end extend in one direction while the diagonal springs at the other end extend in the opposite direction. Thus the pull upon the 105

cable is in opposite directions from the center thereof. This arrangement of supporting helicals not only fills in the space between the upper edge or cable forming a part of the guard and the spring bottom, but also gives to the cable and to the guard as a whole the necessary tension in addition to that which is inherently in the cable when stretched between the uprights or lugs, and moreover, the diagonal springs materially assist in holding the cable taut and under tension, since the pull of these two sets of diagonal springs is in opposite directions.

In practice this side guard may be enclosed in some suitable fabric, as canvas or otherwise as may be found desirable and as shown in Figs. 2 and 3. In the form shown the canvas is provided with suitable fastening buttons or members 9, whereby it may be folded around the guard, the lower end of the canvas being provided with suitable attaching hooks 10 for securing it to the bottom of the guard.

In the form shown in Figs. 4 and 5, the cable is connected directly at its ends to the angle iron end bars by means of helicals or spiral springs 11, while the side guard may be formed as shown in Figs. 1 and 2. As shown however in Figs. 4 and 5 the perpendicular or upright helicals are dispensed with and the diagonal helicals are so located as to be at a greater angle than the diagonal helicals shown in Figs. 1 and 2.

In the organization shown in Figs. 1 and 2, the diagonal helicals at the ends exert a sufficient pull upon the cable guard to enable the cable to be attached directly to the upstanding lugs without the use of helical springs at the ends as shown in Figs. 4 and 5, especially since the helical springs at the ends are connected at their lower ends directly to the transverse irons to which the mattress bottom is connected. It will, of course, be understood that the transverse irons to which the mattress bottom is connected are maintained apart and held in position by suitable side bars 12 connected with the usual brackets carried by the transverse irons, which brackets are ordinarily known as corner brackets and rest upon the bed structure.

By means of the present improvement I am able to provide a simple and comparatively inexpensive side guard having some of the advantages of the metallic fabric side guard, while at the same time, as stated, it may be made somewhat cheaper so that it is more particularly adapted for the less expensive forms of springs, especially as the arrangement of helical springs shown herein gives to the guard a large amount of the tension and resiliency usually present in the metallic fabric guards, while at the same time the organization of springs fills in the space between the cable

and the bottom in an effective manner and which is essential to prevent the protrusion of the stuffed mattress under the cable.

I claim as my invention:

1. A spring mattress comprising a stretched bottom and an upright side guard extending along each longitudinal edge of said bottom and comprising a lengthwise extending cable, and a series of short upwardly extending helical springs, each having its opposite ends connected to said cable and bottom and forming the sole support for the cable between the ends thereof, said helical springs being located at different angles relatively to the bottom and cable. 80

2. A spring mattress comprising a stretched bottom and an upright side guard extending along each longitudinal edge of said bottom and comprising a lengthwise extending cable, and a series of short upwardly extending helical springs, each having its opposite ends connected to said cable and bottom and forming the sole support for the cable between the ends thereof, said helical springs being located at different angles relatively to the bottom and cable, and said helical springs being located relatively close together whereby the space between the cable and the bottom will not be materially larger than the space between any pair of said helical springs. 90

3. A spring mattress comprising a stretched bottom and an upright side guard extending along each longitudinal edge thereof and comprising a lengthwise extending cable, and a series of short upwardly extending helical springs having their opposite ends connected to the cable and the bottom and forming the sole support for the cable between the ends thereof, some of said springs located perpendicularly and some obliquely to the cable and bottom. 100

4. A spring mattress comprising a stretched bottom and an upright side guard extending along each longitudinal edge thereof and comprising a lengthwise extending cable, and a series of short upwardly extending helical springs having their opposite ends connected to the cable and the bottom and forming the sole support for the cable between the ends thereof, some of said springs located perpendicularly and some obliquely to the cable and bottom, and said helical springs being located relatively close together whereby the space between the cable and the bottom will not be materially larger than the space between any pair of said helical springs. 110

5. A spring mattress consisting of a stretched bottom and an upright side guard along each longitudinal edge thereof and comprising a lengthwise extending cable, and a series of short helical springs diagonally positioned relatively to the cable 130

- and the bottom and forming the sole support for the cable between the ends thereof, each having its opposite ends connected to the cable and the bottom.
5. 6. A spring mattress comprising a stretched bottom and an upright side guard along each longitudinal edge thereof and comprising a cable, and short upwardly extending helical springs, each having its opposite ends connected to the cable and the bottom and forming the sole support for the cable between the ends thereof, said helical springs being located to exert a pull upon the guard in opposite directions when the cable is shifted.
10. 7. A spring mattress comprising a stretched bottom, an upright side guard along each longitudinal edge thereof, and a covering for the guard, said guard having buttons for detachably connecting it around the cable and hooks for securing it to the bottom.
15. 8. A spring mattress comprising a stretched bottom, an upright side guard along each longitudinal edge thereof, and a covering for the guard, said covering having means for attaching it to the bottom and around the guard and comprising differently formed means.
20. 9. A spring mattress consisting of transverse irons and a fabric stretched therebetween, an upright side guard along each longitudinal edge of the mattress and comprising a cable stretched under tension, and a helical spring for connecting the cable adjacent to its end with a transverse iron and diagonally located relatively to the mattress.
25. 10. A spring mattress consisting of transverse irons and a fabric stretched therebetween, an upright side guard located along each longitudinal edge of the mattress and comprising a cable stretched under tension, a helical spring connecting the cable adjacent to its end with a transverse iron and diagonally located relatively to the mattress, and a series of short supporting means between the cable and the mattress, each having its opposite ends connected with the cable and the mattress and forming the sole support for the cable between the ends thereof.
30. 11. A spring mattress consisting of transverse irons and a fabric stretched therebetween, an upright side guard along each longitudinal edge of the mattress and comprising a cable stretched under tension, a helical spring connecting the cable adjacent to its end with a transverse iron and diagonally located relatively to the mattress, and a series of short supporting means between the cable and the mattress, each having its opposite ends connected with the cable and the mattress and forming the sole support for the cable between the ends thereof, some of said supporting means being diagonally located relatively to the cable and the mattress.
35. 12. A spring mattress consisting of transverse irons and a fabric stretched therebetween, an upright side guard along each longitudinal edge of the mattress and comprising a cable stretched under tension, a helical spring connecting the cable adjacent to its end with a transverse iron and diagonally located relatively to the mattress, and a series of short supporting means between the cable and the mattress, each having its opposite ends connected with the cable and the mattress and forming the sole support for the cable between the ends thereof, some of said supporting means being diagonally located relatively to the cable and the mattress.
40. 13. A spring mattress comprising a pair of transverse irons, a bottom stretched therebetween, a side guard extending along each lengthwise-extending edge of said bottom, and helicals connecting said side guards directly with said transverse irons of the bottom.
45. 14. A spring mattress consisting of a pair of transverse irons, a fabric stretched therebetween, a side guard along each lengthwise-extending edge of the mattress and connected with said mattress at intervals along the length thereof, and helical springs connecting said side guards directly with the transverse irons of the mattress.
50. 15. A spring mattress consisting of a pair of transverse irons, a fabric stretched therebetween, a side guard along each lengthwise-extending edge of the mattress and connected with said mattress at intervals along the length thereof, and helical springs connecting said side guards directly with the transverse irons of the mattress, said helical springs being located diagonally to the plane of the mattress.
55. 16. A spring mattress consisting of a pair of transverse irons, a fabric stretched therebetween, a side guard along each lengthwise-extending edge of the mattress and connected with said mattress at intervals along the length thereof, helical springs connecting said side guards directly with the transverse irons of the mattress, said helical springs being located diagonally to the plane of the mattress, the means connecting the guard with the mattress consisting of a series of helical springs.
60. 17. A spring mattress consisting of a pair of transverse irons, a fabric stretched therebetween, a side guard along each lengthwise-extending edge of the mattress and connected with said mattress at intervals along the length thereof, helical springs connecting said side guards directly with the transverse irons of the mattress, said helical springs being located diagonally to the plane of the mattress, the means connecting the guard with the mattress consisting of a series of helicals also located diagonally to the plane of the mattress.
65. 18. A spring mattress made up of trans-

- verse irons and a metallic fabric stretched therebetween, an upright side guard located along each lengthwise extending edge of the mattress and comprising a lengthwise extending cable, helical springs directly connecting the ends of said cable with the transverse irons, and a series of short supporting helical springs, each having its opposite ends connected to the cable and the mattress and forming the sole support for the cable between the ends thereof.
19. A spring mattress comprising transverse irons and a metallic fabric stretched therebetween, an upright side guide located along each lengthwise extending edge of the mattress and comprising a lengthwise extending cable, helical springs directly connecting the ends of said cable with the transverse irons, and a series of short supporting helical springs, each having its opposite ends connected to the cable and the mattress, some of said helical spring extending in one direction and some in a different direction.
20. A spring mattress comprising a pair of transverse irons, a bottom stretched therebetween, an upright side guard located along each longitudinal edge of the bottom and comprising a lengthwise extending ca-

ble, and a series of short upwardly extending helical springs located at short intervals along the length of the cable, each having its opposite ends connecting the cable and the bottom, said helical springs being so located as to exert a pull from the center of the guard toward the ends thereof.

21. A spring mattress comprising a pair of transverse irons, a bottom stretched therebetween, an upright side guard located along each longitudinal edge of the bottom and comprising a lengthwise extending cable, a series of short upwardly extending helical springs located at short intervals along the length of the cable, each having its opposite ends connecting the cable and the bottom, said helical springs being so located as to exert a pull from the center of the guard toward the ends thereof, and means for exerting a pull upon the guard in a direction at an angle to that exerted by said helical springs.

Signed at Brooklyn, in the county of Kings and State of New York, this 21st day of September, 1915.

BENJAMIN B. ENGLANDER.
